UNITED STATES PATENT OFFICE.

THOMAS TRESILIAN, OF GLOUCESTER, MASSACHUSETTS, ASSIGNOR TO THE UNION WEB HAMMOCK COMPANY, OF SAME PLACE.

DESIGN FOR A HAMMOCK END RING.

SPECIFICATION forming part of Design No. 12,410, dated August 9, 1881.

Application filed February 19, 1881. Term of patent 3½ years.

To all whom it may concern:

Be it known that I, THOMAS TRESILIAN, a citizen of the United States, residing at Gloucester, in the county of Essex and State of Massachusetts, have invented and produced a new and original Design for Hammock End Rings, of which the following is a specification, reference being had to the accompanying drawing, forming a part thereof.

10 The drawing shows one of my improved rings in plan, this view being deemed sufficient to fully illustrate my design.

The leading feature of my design consists in the part A B C, which is an imitation, in form and general appearances, of a horseshoe, the toe-calk, nail-channels, and nail-heads all being represented.

To the above leading feature—that is, to the parts which represent the heel ends of the horseshoe—I annex to or form in connection therewith the truncated link D E F H, as shown.

I claim—

The design for a hammock end ring, consisting of the horseshoe-shaped part A B C, in combination with the truncated link D E F H, all forming an outline partly in oval and partly in straight lines, as shown.

THOMAS TRESILIAN.
